UNITED STATES PATENT OFFICE.

CLARENCE M. STEINER, OF PITTSBURG, PENNSYLVANIA.

ELECTRICAL CONNECTOR.

988,518.

Specification of Letters Patent.

Patented Apr. 4, 1911.

Application filed July 9, 1910. Serial No. 571,132.

To all whom it may concern:

Be it known that I, CLARENCE M. STEINER, residing at Pittsburg, in the county of Allegheny and State of Pennsylvania, have invented a new and useful Improvement in Electrical Connectors, of which the following is a full, clear, and exact description, reference being had to the accompanying drawings, which form part of this specification.

This invention relates to electrical connectors and particularly to the class more commonly embodying plugs and sockets between which electrical and mechanical connection is made by means of one or more screw-threaded members. Such embodiment is presented in the screw-threaded connection between a standard socket and the base of an Edison incandescent lamp or a correspondingly threaded plug carrying a flexible conductor for connection with a lamp, motor, or other device, and which is commonly known as a cord plug or attachment plug. And the primary object of my invention is the provision in an electrical connector of the above-mentioned type, of means whereby the plug member may be easily and readily attached to and detached from the socket, for making and breaking of the electrical and mechanical connection between the respective members, without extended rotation of the plug.

In connection with an attachment plug my invention will be found particularly advantageous in that it renders it unnecessary to twist and kink the flexible conductor or cord in making the connection above mentioned between the plug and socket.

I also aim to provide means to prevent the loosening and eventual separation of the lamp or the cord plug from the socket, consequent upon vibration.

I will now describe my invention so that others skilled in the art to which it appertains may understand and construct the same, referring to the accompanying drawings in which I have shown my invention as applied to an attachment plug and socket. I do not, however, desire to limit my inven-

tion to the connection shown, as it will be apparent, without necessity of specific illustration, that the same may be applied to incandescent lamps and the like, and to sockets other than the type shown, such as wall sockets.

55

Figure 1 is an elevation of a connected socket and attachment plug, partly in section, and showing my invention as applied to the plug; Fig. 2 is a side elevation of the plug; Fig. 3 is a plan view of the plug; Figs. 4 and 5 are side elevations of modified forms of plugs embodying my invention; Fig. 6 is a side elevational view, partly broken away, showing my invention as applied to a socket adapted to receive a lamp plug or a cord plug; and Fig. 7 illustrates in elevation an ordinary plug to be herein-after more fully referred to.

60

Referring to Figs. 1, 2 and 3, the reference numeral 2 indicates the body of an ordinary attachment plug, formed of suitable insulating material, usually porcelain; this body carries the regular central contact 3 which is adapted to engage the central contact 4 of a socket, such as the ordinary lamp socket indicated by the numeral 5, and the outer band or sleeve contact 6 which is adapted to be received by and from electrical contact with the sleeve or shell 7 of the socket. This circuit terminal in the form of the sleeve 6 ordinarily comprises a non-yielding band, screw-threaded for substantially its full length in complement with the screw-threaded shell 7 of the socket. In the present improved construction of my invention, I longitudinally slot or cut away the sleeve 6 as indicated by the numeral 8, forming thereby the resilient tongues or fingers 9, which permit of the plug being thrust into the socket pending positive attachment of the sleeve 6 with the threaded shell 7 by means of the screw-threads 10 carried below the tongues or fingers 9 by the non-yielding base of the plug. Temporary connection of the plug with the socket, pending such positive locking of the members, is effected by means of the threads or protuberances 11 carried by

75

the yieldable fingers 9 and which skip past and co-operatively engage with the threaded interior of the shell 7, when the plug is thrust thereinto. The threads 10 are preferably so disposed as to allow of their being shifted into positive engagement with the threads of the shell 7, by substantially only one turn or revolution of the plug, after the latter has been thrust in the socket the full depth permissible by the resiliency of the fingers 9. It will be seen that, in my improved connection, there is no tendency to formation of destructive arcs upon the direct insertion of the plug, for the rotative feeding of the plug to positive engagement with the socket presents the center contact of the plug to that of the socket in the usual manner.

I do not desire to limit myself to the particular form of sleeve 6 shown in Figs. 1. 2 and 3. For instance, in Fig. 4 I show a somewhat modified construction in which the fingers 9 are provided each with the single protuberance or thread 11* instead of being threaded for their full depth in the manner shown in Fig. 1. Also, as shown in Fig. 5, the number of the resilient fingers 9 may vary. In this view these fingers are greater in number and of a somewhat narrower construction than the fingers shown in the views 1, 2 and 3.

Referring to Fig. 6, I show a reversion of the construction shown in the preceding figures. In this construction resilient fingers 9' corresponding in function to the fingers 9 of the plug, are carried by the shell 7 of the socket. This form of shell is adapted to receive the usual form of threaded plug 13, illustrated in Fig. 7. The yielding fingers 9' permit, as in the case of the fingers 9, of the plug being thrust into the socket and there being temporarily held by the threads 13, pending positive attachment. In this case such positive connection is made between the threaded top of the plug and the non-yielding upper portion 14 of the shell 7, by means of the suitable interior threads 15. The slotting of the shell 7 of this socket shown in Fig. 6 corresponds substantially with that of the plug shown in Fig. 5, but may be varied as desired without departing from my invention.

The fingers 9 and 9' are preferably so disposed as to cause them to bear, by reason of their resilient nature, respectively in the first case against the interior of the socket 7, and in the latter case against the sleeve 6 of the plug 2, so as to create such frictional resistance as shall operate against accidental unscrewing of the attached plug from the socket, through vibration.

As stated above, my invention is not limited to the attachment plug and socket

arrangement, but is equally applicable to correspondingly threaded plug members, 65 such as an incandescent lamp base, plug fuses, or similar device etc. And while I have described the sleeves or shells 6 and 7 as forming electrical terminals, it is obvious that there would be no departure from my 70 invention to employ these members independently of electrical terminal service.

It will be apparent that many other changes may be made in the construction shown without departing from my invention 75 and I do not therefore desire to limit myself thereto.

Having thus described my invention, what I claim and desire to secure by Letters Patent is:

1. In a device of the character described, the combination of a body portion, means carried thereby for effecting rotative positive attachment to a body adapted for co-operative connection therewith, and yieldable means carried by the body portion, for effecting supporting engagement thereof with the body, pending such positive attachment.

2. In a device of the character described, 90 the combination of a body portion, a threaded sleeve carried thereby for effecting rotative positive attachment to a body adapted for co-operative connection therewith, and yieldable means carried by the body portion, 95 for effecting supporting engagement thereof with the body, pending such positive attachment.

3. In a device of the character described, the combination of a body portion, a threaded sleeve carried thereby for effecting rotative positive attachment to a body adapted for co-operative connection therewith, and yieldable means carried by the sleeve, for effecting supporting engagement thereof with the 105 body, pending such positive attachment.

4. In a device of the character described, the combination of a body portion, a threaded sleeve carried thereby for effecting rotative positive attachment to a body adapted for co-operative connection therewith, and a yieldable finger carried by the body portion, for effecting supporting engagement thereof with the 110 body, pending such positive attachment.

5. In a device of the character described, the combination of a body portion, a sleeve carried thereby for effecting rotative positive attachment to a body adapted for co-operative connection therewith, and a yieldable finger carried by the sleeve for effecting supporting engagement thereof with the 115 body, pending such positive attachment.

6. In a device of the character described, the combination of a body portion, and a 120 cylindrical sleeve carried thereby, the sleeve

being longitudinally slotted from one end for a portion of its length and provided with a protuberance lying outside the zone of the slots and adapted for effecting locking engagement between the sleeve and a body adapted for coöoperative association therewith.

In testimony whereof, I have hereunto set my hand.

CLARENCE M. STEINER.
